(57) **CLAIM**

The ornamental design for a luminaire, as shown and described.

DESCRIPTION

FIG. 1 is a bottom-front-right oblique view of a luminaire showing my new design.

FIG. 2 is a top-front-right oblique view of a luminaire showing my new design.

FIG. 3 is a top view of a luminaire showing my new design.

FIG. 4 is a front view of a luminaire showing my new design.

FIG. 5 is a bottom view of a luminaire showing my new design.

FIG. 6 is a rear view of a luminaire showing my new design; and,

FIG. 7 is a right side view of a luminaire showing my new design.

The broken lines shown on the drawings depict environment only and form no part of the claimed design.
